DESIGN FOR A DRINKING GLASS

James E. Spence, Wheeling, W. Va., assignor to Hazel-Atlas Glass Company, Wheeling, W. Va., a corporation of West Virginia

Application January 24, 1940, Serial No. 89,683

Term of patent 14 years

To all whom it may concern:

Be it known that I, James E. Spence, a citizen of the United States, residing at Wheeling, in the county of Ohio and State of West Virginia, have invented a new, original, and ornamental Design for a Drinking Glass, of which the following is a specification, reference being had to the accompanying drawing, forming part thereof.

I claim:

The ornamental design for a drinking glass, as shown.

JAMES E. SPENCE,
